UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL MINING APPARATUS

Application filed October 16, 1929. Serial No. 400,063.

This invention relates to new and useful improvements in mining machines.

An important object of the invention is to provide an improved elevating mechanism 5 for the coal cutting instrumentality mounted on the truck frame.

Another important object of the invention is to provide an elevating mechanism of the above character which dispenses with 10 the necessity of using different size pedestals to attain the required elevations of the coal cutting instrumentality, said elevating mechanism including a sectional pedestal comprising a plurality of telescopic floating 15 guides which serve in maintaining the coal cutting instrumentality in a state of rigidness heretofore found impossible with the elevating mechanism heretofore employed.

A still further object of the invention is 20 to provide a coal mining machine elevating mechanism with a compound screw elevator thereby increasing the speed of vertical adjustments.

Other objects and advantages of the invention will become apparent during the 25 course of the following description.

In the accompanying drawings, forming a part of the description and wherein like numerals are employed to designate like 30 parts throughout the several views:

Figure 1 is a top plan of an arcwall mining machine.

Figure 2 is a bottom plan of the same on an enlarged scale illustrating the driving 35 means for the elevating mechanism, as well as the means of locomotion of the mining truck.

Figure 3 is an enlarged vertical section through one of the improved elevating screw 40 mechanisms taken along the line 3—3 of Figure 1.

Figure 4 is a similar section of the elevating screw mechanism with the mechanism extended to its full height.

Figure 5 is a transverse section taken through the mechanism on the line 5—5 of Figure 4.

Figure 6 is a transverse section taken 50 through the elevating mechanism on the line 6—6 of Figure 3.

Figure 7 is an enlarged section of the lower end of one elevating mechanism illustrating the clutch operator.

Figure 8 is a sectional view of the drive mechanism taken on line 8—8 of Figure 2. 55

Figure 9 is a sectional view taken along line 9—9 of Figure 8.

Figure 10 is a diagrammatic view of the gearing illustrated in Figure 8, and

Figure 11 is a perspective view of the 60 clutch shifting devices associated with the gearing illustrated in Figures 8 and 9.

In the present illustration of the invention, I have elected to show the present invention as applied to an arcwall mining machine 65 of the usual type which is power driven along track rails, but it is to be understood that the invention may be applied to any type of mining machine.

Referring now more particularly to the 70 drawings, the numeral 1 designates the main frame of a mining machine equipped with a pair of axles 2, provided with traction wheels 3, driven from the usual electric motor 4 through power devices 5 and 75 sprocket chains 6 and 7. Suitable control mechanisms are provided for controlling the electric motor and for clutching the axle drives to the power devices, which will now be described.

Fixed to the forward axle 2 is a brake drum 60 which is encircled by a brake band 61 connected by a toggle 62 and link 63 with a transverse shaft 64 mounted in suitable bearings upon the truck frame. To 85 the shaft 64 is fixed a rocker arm 65 which is connected by a rod 66 with the operating lever 67, of well-known design, adapted to be held in retracted position by the notched ratchet plate 68. By manipulation of the lever 67 tension may be applied to the brake band 61 to exert a retarding force upon the brake drum 60 to resist rotation of the axle 2, and by engagement of the operating lever 67 with the ratchet plate 68 the tension of 90 the brake band may be maintained at the will of the operator.

Mounted upon the truck frame is the electric motor 4 which supplies power for the propulsion of the carriage and for the ac- 100

tuation of the auxiliary devices associated therewith, including the elevating mechanisms. The armature shaft of the motor 4 is connected with a longitudinally extending 5 worm shaft 69, journaled in suitable bearings of the gear housing 70, by a jaw clutch coupling 71. The gear housing 70 is bolted to an extension floor plate 72 which projects rearwardly of the truck frame to form a step 10 upon which the operator may ride when the machine is traveling from one working place to another. This method of connecting the motor 4 with the worm shaft 69 affords a desirable flexibility between the power units and permits the removal of either of these parts without disturbing the other. Formed upon the worm shaft 69 is a worm 15 73 which engages a worm wheel 74 mounted for free rotation upon the truck propelling shaft 75 which extends transversely of the truck frame and is supported in journal bearings of the gear housing 70. The worm wheel 74 is arranged to be connected with the truck propelling shaft 75 by a suitable 20 friction clutch 76 arranged to be controlled by the lever 77 adapted to rotary oscillation about the truck propelling shaft 75. A brake drum 76' fixed to the truck propelling shaft 75 is encircled by a brake band 77', 25 the tension of which is controlled by movement of the lever 77 which also controls the friction clutch 76. The arrangement of these parts is such that movement of the lever 77 in one direction from its central 30 neutral position causes the actuation of the clutch 76 to drive the shaft 75, and movement of said lever in the opposite direction from this central neutral position applies a retarding force to the brake drum 76' to 35 resist rotation of said shaft.

Attached to the extension floor plate 72 is a second gear casing 78 having suitable bearings, in which is supported an extension shaft 79 in longitudinal alignment with the 40 truck propelling shaft 75. The shafts 75 and 79 are operatively connected by a jaw clutch coupling 80 which affords a degree of flexibility very desirable in machinery of this class. Upon this extension shaft 79 is 45 mounted for free rotation relative thereto a spur gear 81 having an integral extension sleeve 82 to which is fixed a second gear 83. The gear 83 meshes with a spur gear 84 fixed to one end of a countershaft 85, and to 50 the other end of this countershaft 85 there is fixed a sprocket wheel 86 which engages the truck propelling chain 6 to drive it. The countershaft 85 is supported in parallelism with the extension shaft 79 in a sleeve bearing 87 which is suspended upon supporting pins 88 fixed to the gear housing in such manner that the sprocket wheel 86 may be moved longitudinally of the truck frame to 55 adjust the tension of the driving chain 6.

65 Two oppositely disposed set screws 89 are

screw threaded in suitable apertures of the gear housing casting to afford means for effecting the adjustment of the sleeves 87 and the tensioning of the chain 6.

Fixed to the outer end of the extension shaft 79 is a spur pinion 90 in engagement with a spur gear 91 fixed to the back gear shaft 92, supported in bearings of the gear housing and extending parallel with the shaft 79. A spur pinion 93 is slidably mounted upon the back gear shaft 92 and is rotatably connected therewith by a suitable feather key, and this pinion 93 is adapted to be moved into and out of engagement with the spur gear 81. Movement of the pinion 93 is controlled by the shifting yoke 94 fixed to the shaft 95, which is longitudinally slidable in apertures of the gear housing. A pin 96 projecting laterally from the shaft 95 affords a handle for the manipulation of the pinion 93.

Mounted upon the extension shaft 79 is a bevel pinion 97 formed integral with a sleeve 98 which extends through the journal bearings 99 of the gear housing, and upon the inner end of this sleeve 98 is formed a clutch member 100 adapted to engage with teeth formed on the outer face of the jaw clutch 101 when it is moved to its extreme right hand position. The bevel pinion 97 engages the bevel gear 102 loosely mounted upon the upper end of a vertical shaft 103 which is journaled in suitable bearings of the gear housing. Removably mounted upon the shaft 103 adjacent the bevel gear 102 is a plate 104 having an aperture adapted for alignment with vertical aperture in the bevel gear 102 for the reception of a shear pin 105. Beneath this removable plate 104 is a collar 106 turned integral with the shaft 103, and it also has an aperture for the reception of the lower end of the shear pin whereby the shear pin forms the connection for the bevel gear 102 to the shaft 103. The purpose of this removable plate 104 is to enable it to be replaced in case its aperture for the shear pin becomes unduly enlarged through wear. The gear casing 78 beneath the collar 106 is provided with an aperture 107 through which broken shear pins may fall by gravity onto the extension floor plate 72. To the vertical shaft 103 is fixed a sprocket wheel 108 which engages the driving chain 17 for the actuation of the elevating mechanisms hereinafter described.

Movement of the jaw clutch 101 is controlled by the shifting yoke 109 attached to a shifting lever 110 which is pivotally supported in the gear housing 78. A controlling handle 111 attached to the shifting lever 110 and positioned outside of the gear housing 78 affords means for moving the clutch 101. A spring-pressed dog 112 adapted to engage either of three apertures in the gear housing casing, serves to hold the parts in

either of three positions of adjustment. When the hand lever 111 is moved to its extreme left hand position the clutch 101 engages teeth formed on the face of spur gear 83 to connect it directly with the shaft 79. When the hand lever 111 is in its extreme right hand position, the clutch 101 engages the clutch member 100 to connect the bevel pinion 97 with the shaft 103. When the 10 operating lever is in its central position the clutch 101 is held out of engagement with either the spur gear or the bevel gear.

Formed on the clutch shifting lever 110 is a crank arm 113 to which is connected 15 the upwardly projecting interlocking bar 114 at the upper end of which is provided an aperture 115 through which projects the shaft 95. Formed in the shaft 95 is a notch 116 adapted to register with the interlocking 20 bar 114 when the pinion 93 is in its position of disengagement from the gear 81. The shape and proportions of this aperture 115 are such that the interlocking bar 114 is held against vertical movement when the 25 pinion 93 is in its position of engagement, thereby preventing shifting of the clutch 101 during such engagement, and the shaft 95 is held against longitudinal movement when the clutch 101 is in either of its 30 positions of engagement, thereby preventing movement of the spur pinion 93 to engaged position when the clutch 101 is in either of its positions of engagement.

By the arrangement of parts above described, the power may be transmitted from the motor 4 through the truck propelling shaft 75, clutch 101, spur gears 83 and 84, sprocket wheel 86, and chain 6 to propel the truck at a relatively high speed, or 40 power may be transmitted through the truck propelling shaft 75, spur gears 90, 91, 93 and 81 to the spur gear 83, and through the gear 84, sprocket wheel 86 and chain 6, to propel the truck at a relatively low speed, 45 and the interlocking mechanism is adapted to prevent the actuation of the gearing in antagonistic combinations.

It will also be obvious that movement of the clutch 101 to the right of Figure 8 causes engagement of the clutch face 100 of the bevel gear 97 causing it to rotate with extension shaft 79 and operates bevel gear 102, and through the shear pin 105 causes rotation of the sprocket 108 to drive 55 elevating mechanisms which will now be described.

As is customary in the arcwall mining machines, a rotary bed frame or support 8 is revolvably mounted for the usual adjustments upon a supporting ring 9 and carries a radially projecting coal mining instrumentality in the form of an elongated frame or arm about which travels, in a horizontal plane, an endless coal cutting chain carrying 65 the usual coal cutter bits. Suitable

drive means for the cutter chain are provided as well as controls for starting and stopping the same and suitable means are also provided for turning the table 8 to move the kerf cutter from side to side of the machine in an arc, as well as for locking the turntable in any desired position to retain the kerf cutting arm 10 in the desired angular extension from the mining machine to perform coal mining operations.

In order to cut kerfs in veins of coal at different elevations from the mine floor, it is necessary to provide an elevating mechanism for the support of the coal mining instrumentality and heretofore this has been accomplished by placing three single screw elevating mechanisms between the mining machine frame and the support for the coal cutting instrumentality. To hold the coal cutting mechanism substantially rigid during mining operations different size pedestals had to be employed for different elevations of the coal cutting mechanism. In order to provide for a wide range of vertical adjustments of the coal cutting instrumentality without the necessity of requiring several different size pedestals, the present improved elevating mechanism has been devised and has been found to not only give increased speed of elevation but to add substantial rigidity in the support of the coal cutting mechanism when in operation.

This improved elevating mechanism consists primarily of three compound screw mechanisms indicated in their entirety by the numeral 11 positioned upon the mining machine frame 1 at points substantially equi-distant around the turntable 8, it being observed that two of the elevating devices are arranged at the two forward corners of the mining machine and the third on the longitudinal center line of the frame at the side of the turntable opposite the two forward elevating mechanisms. As all of the elevating mechanisms are of the same construction, and have the same mode of operation, a description of one will be given for all.

Each compound screw elevating mechanism comprises a step bearing 12 bolted to the underside of the mining machine frame 1 and to each stepped bearing is bolted a longitudinally extensible pedestal indicated in its entirety by the numeral 13. Mounted within the stepped bearing is a bushing 14 forming a bearing for a vertically disposed drive sleeve 15. Loosely mounted upon this sleeve is a sprocket wheel 16 operated by a sprocket chain 17, as clearly shown in Figures 2 and 7, driven by the sprocket 108 forming a part of the power transmission devices 5. This sprocket chain is trained about the sprockets 16 of all three elevating mechanisms as shown for operating them. Clutch mechanisms to be hereinafter de-

scribed are provided for each sprocket 16 whereby it may be individually controlled for causing the kerf cutting arm 10 to be angularly disposed to the horizontal for cutting out dirty seams of coal, as will be more fully described hereinafter.

Bolted to the upper side of the mining machine frame is a nut pedestal 19 arranged concentric with the drive sleeve 15 and above 10 the same as shown to form a bearing for the upper end of the same. This nut is equipped with left hand threads to cooperate with the left hand threads provided upon the exterior of a screw sleeve 20 provided with diametrically opposed longitudinal grooves 21 in its exterior for cooperation with the drive sleeve 15 for rotating the screw sleeve 20 by means of a clutch collar 23 feathered to the drive sleeve 15, as 15 at 24 and having a clutch face cooperating with a clutch face 25 provided on the upper end of the sprocket 16, as shown in Figure 7.

The screw sleeve 20 is also equipped with 20 internal right hand threads for the reception of a right hand screw 26 held against rotation by a collar 27 thereon having a non-circular reduced portion 28 fitting within a corresponding opening in the uppermost floating guide 29 of the pedestal 13. The threads of all three of these members are preferably of the same pitch but in case a greater range and speed adjustment is required, the pitch of the threads of screw 26 25 may be made greater than that of the screw sleeve 20. The upper end 30 of the screw 26 is reduced above the reduced portion 28 to extend through a sleeve 31 having its lower end seated in a recess of the floating 30 guide 29. This sleeve 31 is equipped with an external shoulder 32 against which seats one end of a coil spring 33, the upper end of which abuts a washer 34 held upon the reduced end of the screw 26 by means of a 35 nut 35. This nut may be turned to adjust the tension of the coil spring 33 as required. This sleeve 31 extends through an opening in a cup-shaped bracket 36 secured to the outer periphery of the ring 9 and it is to 40 be noted that the sleeve has a loose fit in this bracket so that when desired, only one compound screw mechanism may be operated to tilt the kerf cutter and supporting table 8, as hereinbefore mentioned.

50 The upper floating guide section 29 is provided with a pair of depending flanges 37 equipped with a pair of diametrically opposed depending flanges 38 for engagement with the inwardly extending flanges of a 55 second floating pedestal section 39 within which the upper section 29 is telescoped. The section 39 is provided on its interior with a vertically disposed groove 40 in which a projection 41 of the bracket 36 operates when the elevating mechanism is

lowered and the floating guides telescope as indicated in Figure 3. Upon elevation of the screw 26 and upper pedestal section 29, the latter will move out of the section 39 and cause elevation of the latter by means 70 of lugs 42 of the section 29 engaging beneath stops 43 of the section 39, as illustrated in Figure 4.

The floating section 39 of the pedestal is adapted to telescopically slide within a third 75 floating substantially U-shaped rigid section 44 of the extensible pedestal and is provided with a block 45 removably secured thereto by means of a set screw 46 to operate with in a vertically disposed groove 47 of section 80 44. The block 45 slides upwardly of the groove 47 upon elevation of the section 39 until it is carried into engagement with the upper end of the groove when it causes elevation of the section 44. When the elevating mechanism is lowered, the block 45 slides down the groove 47 until it engages the lower end thereof, thereby causing descent of section 44. This latter section is equipped with an opening 48 which is adapted to 85 register with an opening 49 in a stationary pedestal section 50 which is bolted to the stepped bearing, as hereinbefore stated, when the elevating mechanism is in its lowered position in order that the block 45 90 may be removed and the floating sections of the pedestal disassembled.

In order to limit the outward movement of the section 44 with respect to the lowermost section 50, a shoulder 51 is provided 100 within the latter for engagement with a projection 52 carried at the lower end of section 44.

As shown most clearly in Figures 5 and 6, the three lowermost sections 50, 44 and 39 of the extensible pedestal are of substantially rectangular or U-shape in cross-section with inturned flanges 53 of each section embracing corresponding inturned flanges of the next uppermost section. This construction, while permitting free sliding or telescoping movement of one section within the other, provides an extremely rigid extensible support whether the sections of the pedestal are extended or collapsed, and this provides for the rigid unfaltering support of the coal mining instrumentality. 110

As shown, lubricant grooves are provided on the contacting surfaces of the floating sectional guides to insure thorough lubrication and easy sliding operations.

The two clutch members 23 of the two forward elevating screws are each provided, as shown, in Figure 2, with a clutch shifting member 54 connected by a rocker arm 55 to a lever 56 extending along the side of the mining machine frame to the rear thereof and terminating on the upper side in a handle 57 which may be conveniently manipulated by the operator for causing inde- 125 130

pendent or simultaneous operation of the two forward screw mechanisms to the exclusion of the third screw mechanism. The third screw elevating mechanism located 5 along the center line of the machine is provided with a similar independent clutch operating mechanism having a clutch operating handle 58 by which this mechanism may be independently controlled for causing individual elevation of this elevating mechanism to the exclusion of the other two elevating mechanisms for tilting the kerf cutter arm 10 in a downward direction. When either of the two screw elevating mechanisms 10 at the forward end of the machine are operated to the exclusion of the other two elevating screws, the kerf cutting arm 10 is tilted upwardly at an incline, and obviously when all three elevating mechanisms are operated in unison, the kerf cutting arm and its support will be adjusted vertically uniformly, in order that the kerf cutting arm 10 may be raised and lowered in a perfectly horizontal position.

25 When the clutch collar 23 of any of the three screw mechanisms is lowered into engagement with the clutch face 25 of sprocket 16 and the latter is being rotated, the drive sleeve 15 is caused to rotate. This rotation is conveyed to the screw sleeve 20 through the gib keys 22, thereby causing the same to grow out of the pedestal nut 19 and simultaneously cause the extension of screw 26 from the screw sleeve 20 due to the fact that the screw 26 is prevented from rotation and the right and left hand thread arrangement of the compound screw causes simultaneous extension of the screw sleeve 20 and screw 26. As the compound screw elongates in elevating the cutting mechanism support, the upper floating guides or section 29 of the pedestal is elevated until its lugs 42 engage beneath the stops 43 of the second floating section 39, thereby causing movement of the same with the screw mechanism. Elevation of this section 39 causes successive elevation of the section 44 by reason of the block 45 engaging the upper end of groove 47 and section 44 may be elevated until its stop lug 52 contacts with a shoulder 51 of the lower pedestal section 50. In order to prevent serious damage to the operating mechanism after the stop 52 engages the shoulders 51, the shear pin 105 will shear off, thereby preventing damage to the power devices and elevating mechanisms.

On downward movement of the elevating mechanism this shear pin will shear if the clutch mechanism is not disengaged when the collar 27 of screw 26 engages the upper end of screw sleeve 20, or in case of the operation of one screw only when the mining machine element is angled to its maximum

limits, said pin will shear and prevent serious damage.

It is to be understood that various changes in the size, shape and arrangement of parts may be resorted to without departing from the scope of the appended claims.

What I claim is:—

1. The combination with a mining machine, a coal cutting device vertically and horizontally adjustable thereon; of self-contained power means for vertically adjusting said device and being subject to lateral thrusts imposed by the cutting device, and a longitudinally extensible pedestal associated with said power means to brace the latter against said lateral thrusts.

2. The combination with a mining machine, a support for a coal cutting device mounted thereon, said support including a vertically adjustable part for supporting a horizontally adjustable part; of a screw connected to said vertically adjustable part for moving the same, and a longitudinally extensible pedestal associated with said screw.

3. The combination with a mining machine, a support for a coal cutting device mounted thereon, said support including a vertically adjustable part for supporting a horizontally adjustable part; of a double action screw connected to said vertically adjustable part for moving the same, and a longitudinally extensible pedestal associated with said screw means.

4. The combination with a mining machine frame, a support for a coal cutting device vertically adjustable thereon, a compound screw mounted on said frame and loosely connected to said support for vertically adjusting the latter, and a longitudinally extensible pedestal connecting said screw and frame and including means for preventing rotation of a section of said compound screw.

5. The combination with a mining machine frame, a support for a coal cutting device vertically adjustable thereon, a compound screw mounted on said frame and loosely connected to said support for vertically adjusting the latter, and a longitudinally extensible pedestal connecting said screw and frame and including a non-rotary sliding section connected with a section of said screw to prevent rotation thereof.

6. The combination with a mining machine frame, a support for a coal cutting device vertically adjustable thereon; of a double action screw mounted on said frame and having a non-rotary section loosely depending from said support, and a longitudinally extensible telescopic pedestal connected to said non-rotary section and to said machine frame.

7. The combination of a mining machine frame, a support for a coal cutting device vertically adjustable thereon, of a double

- action screw mounted on said frame and having a non-rotary screw section depending from said support, said section having a non-circular shoulder, and a longitudinally extensible sectional pedestal having a section supported on said shoulder and slidably associated with an adjacent section to prevent rotation of said screw section.
8. The combination with a mining machine frame, a support for a coal cutting device vertically adjustable thereon; of a pedestal nut secured to said frame, a screw sleeve operating through said nut and having an internal thread, a non-rotary screw threaded into said sleeve and connected to said support, a rotary sleeve embracing said screw sleeve and splined thereto, and means for actuating said rotary sleeve.
9. The combination with a mining machine frame, a support for a coal cutting device vertically adjustable thereon; of a nut secured to said frame, a screw sleeve operating through said nut and having an internal thread, a non-rotary screw threaded into said sleeve and connected to said support, a bearing below said nut and arranged concentric therewith, a drive sleeve mounted in said bearing below said nut and splined to said screw sleeve, a driving member, and clutch means between the same and said drive sleeve.
10. The combination with a mining machine frame, a support for a coal cutting device vertically adjustable thereon; of a nut secured to said frame, a screw sleeve operating through said nut and having an internal thread, a non-rotary screw threaded into said sleeve and connected to said support, a bearing below said nut and arranged concentric therewith, a drive sleeve mounted in said bearing below said nut and splined to said screw sleeve, a sprocket loosely mounted on said drive sleeve and having a clutch face, and a clutch member cooperating with said clutch face and feathered upon said drive sleeve.
11. The combination with a mining machine frame, a support for a coal mining device vertically adjustable thereon, of a plurality of double action screws mounted on said frame and loosely connected to said support, and a longitudinally extensible pedestal of rigid telescopic slidable sections for each screw connected to said frame and screw and permitting said support to be angularly disposed on said screws while retaining its rigidity.
12. The combination with a mining machine, a coal cutting device, a support therefor subject to lateral thrusts imposed by the cutting device; of double action screw means connected to the support for vertically adjusting the same, and a longitudinally extensible pedestal associated with said screw means to brace the latter against said lateral thrusts.
13. The combination with a mining machine, a coal cutting device, a support therefor subject to lateral thrusts imposed by the cutting device; of double action screw means connected to the support for vertically adjusting the same, and a telescopic pedestal partially housing said screw means and connecting said machine and support for bracing the screw means against lateral thrusts.
14. The combination with a mining machine, a coal cutting device, a support therefor subject to lateral thrusts imposed by the action of the cutting device; of double action screw means for vertically adjusting said support, and a sectional telescopic pedestal connecting said machine and support and bracing said screw means against said lateral thrusts.
15. The combination with a mining machine, a support for a coal cutting device vertically adjustable thereon; of a screw loosely associated with said support to permit lateral tilting of the same, a rotary screw sleeve operable upon said screw, and a sectional telescopic pedestal connecting said machine and support and having connection with said screw to prevent turning thereof.
16. The combination with a mining machine, a support for a coal cutting device vertically adjustable thereon; of a screw loosely depending from said support for vertically adjusting the same and to permit lateral tilting of the support, a rotary sleeve operable upon said screw, and a sectional telescopic pedestal connecting said machine and support and having connection with said screw to prevent turning thereof.
17. The combination with a mining machine, a support for a coal cutting device vertically adjustable thereon and having an apertured part; of a screw extending through said apertured part and having a shoulder for supporting the same, a rotatable screw sleeve operable upon said screw, and a sectional telescopic pedestal connecting said machine and support and having connection with said screw to prevent turning thereof.
18. The combination with a mining machine, a support for a coal cutting device vertically adjustable thereon, a screw loosely associated with said support for vertically adjusting the same, a screw sleeve operable upon said screw, a sectional telescopic pedestal connecting said machine and support and having connection with said screw to prevent turning thereof, and said pedestal sections having cooperative flat faces slidingly engaged for steadyng said screw.
19. The combination with a mining machine, a support for a coal cutting device vertically adjustable thereon, a screw loose-

ly associated with said support for vertically adjusting the same, a screw sleeve operable upon said screw, a sectional telescopic pedestal connecting said machine and support and having connection with said screw to prevent turning thereof, and said pedestal sections comprising substantially open sided rectangular members telescopically associated.

10 20. The combination with a mining machine frame, a support for a coal cutting device; of a nut secured to said frame, a screw sleeve operating through said nut and having an internal thread, a non-rotary screw threaded into said sleeve and connected to said support, a rotary sleeve concentric with said screw sleeve and splined thereon, a clutch element feathered to said rotary sleeve, and a cooperating driving 55 clutch member loosely mounted on said rotary sleeve and adapted for engagement with said clutch element.

25 21. The combination with a mining machine frame, a support for a coal cutting device; of a nut secured to said frame, a screw sleeve operating through said nut and having an internal thread, a non-rotary screw threaded into said sleeve and connected to said support, a bearing below said nut and arranged concentric therewith, a drive 60 sleeve mounted in said bearing below said nut and splined to said screw sleeve, said drive sleeve having its upper end engaging said nut, and means for actuating said drive sleeve.

30 35 22. The combination of a mining machine frame, a support for a coal cutting device; of an elevating device including a screw for vertically adjusting said support, said screw having a supporting shoulder, and an extensible pedestal connected to said machine and including a section supported upon said shoulder.

40 45 50 23. The combination of a mining machine frame, a support for a coal cutting device; of an elevating device including a screw for vertically adjusting said support, said screw having a supporting shoulder, and an extensible pedestal connected to said machine and including a section supported upon said shoulder, said shoulder having a noncircular portion engaging said section to prevent turning of the screw.

55 60 65 24. The combination with a mining machine frame, a support for a coal cutting device, an apertured bracket carried by said support, an elevating device mounted on the frame and including a screw having its upper end extended loosely through said bracket, an extensible pedestal connected to said screw, a shouldered sleeve mounted on the upper end of said screw and extended through said apertured bracket, a coiled spring surrounding said sleeve and support-

ed on the shoulder thereof, and adjustable means on said screw abutting said spring.

25 55 70 75 25. In a mining machine, a base, a support, a cutting instrumentality on said support, a plurality of screw and nut units interposed between the base and support and operable to elevate and lower the support and to carry the weight thereof, and telescopic pedestals extending between the base and the support, said pedestals including upper sections in connection with the support and lower sections secured to the base independently of said units to transmit to the base independently of said units lateral thrusts exerted on the support by the cutting instrumentality.

80 85 90 95 26. In a mining machine, a base, a support, a cutting instrumentality on said support, a plurality of screw and nut units interposed between the base and support and operable to elevate and lower the support and to carry the weight thereof, and telescopic pedestals extending alongside the screw and nut units between the base and support, said pedestals including upper sections in connection with the support and lower sections secured to the base independently of said units to transmit to the base independently of said units lateral thrusts exerted on the support by the cutting instrumentality.

100 105 110 115 27. In a mining machine, a base, a support, a cutting instrumentality on said support, a plurality of screw and nut units interposed between the base and support and operable to elevate and lower the support and to carry the weight thereof, and telescopic pedestals extending alongside the screw and nut units between the base and the support and partially surrounding said units, said pedestals including upper sections in connection with the support and lower sections secured to the base independently of said units to transmit to the base independently of said units lateral thrusts exerted on the support by the cutting instrumentality.

120 125 130 28. In a mining machine, a base, a support, a cutting instrumentality on said support, a plurality of screw and nut units interposed between the base and support and operable to elevate and lower the support and to carry the weight thereof, and a telescopic pedestal extending between the base and the support, said pedestal comprising sections non-rotatable relative to each other, the uppermost section being connected to the support and the lowermost section being secured to the base independently of said units to transmit to the base independently of said units lateral thrusts exerted on the support by the cutting instrumentality.

29. In a mining machine, a base, a support, a cutting instrumentality on said support, a plurality of screw and nut units in-

terposed between the base and support and operable to elevate and lower the support and to carry the weight thereof, and telescopic pedestals extending alongside the screw and nut units between the base and the support, said pedestals comprising sections non-rotatable relative to each other, the uppermost sections being connected to the base independently of said units to transmit to the base independently of said units lateral thrusts exerted on the support by the cutting instrumentality, said uppermost sections being also connected to portions of the adjacent screw and nut units to prevent rotation thereof.

30. The combination with a supporting frame, of coal cutting mechanism mounted thereon for lateral feeding movement relatively thereto, spaced-apart individually extensible pedestals for adjustably supporting said coal cutting mechanism on said frame, means for individually adjusting the extensions of said pedestals, and extensible means associated with each pedestal to brace the latter against lateral thrusts during lateral feeding of said cutting mechanism into the coal.

31. The combination with a supporting frame, of a supplemental frame, a coal cutting device mounted on said supplemental frame for lateral swinging feeding movement therewith, double action screw mechanism for adjusting the elevation of said supplemental frame and said coal cutting device, and extensible bracing means associated with said screw mechanism to resist lateral thrusts due to lateral feeding movement of said coal cutting device.

32. The combination with a mining machine frame, of coal cutting mechanism vertically adjustable thereon, a nut secured to said frame, a screw operable through said nut and internally screw-threaded, a non-rotary screw threaded into said sleeve and connected to said coal cutting mechanism, a drive sleeve connected to said first mentioned screw, a driving member, and a clutch for connecting said driving member to said drive sleeve.

33. The combination with a supporting frame, of a coal mining device, a plurality of spaced-apart double action screw supports for said coal mining device, and a plurality of extensible bracing structures one for each of said screw supports and each comprising longitudinally extensible rigid telescopic slidable sections co-acting with the adjacent screw support.

34. The combination with a supporting frame, of a supplemental frame, mining mechanism mounted on said supplemental frame, means comprising an elevating screw device for adjusting the elevation of said supplemental frame and the mining mechanism thereon, and an extensible brac-

ing structure associated with said screw device and comprising a plurality of telescoping slidable sections between the supporting frame and the supplemental frame and each C-shaped in cross-section.

35. The combination with a mining machine frame, of coal cutting mechanism, means comprising a screw post for adjusting the elevation of said cutting mechanism, lateral bracing structure associated with said post and comprising a vertical guide section fixed to said frame, an upper guide section carried at the upper end of said post, and intermediate guide sections and abutments between the next adjacent guide sections for limiting the extension of the post and said bracing structure and thereby limiting the elevation of said cutting mechanism.

36. The combination with a supporting frame, of mining mechanism, means comprising a non-rotatable screw for adjusting the elevation of said mining mechanism, mechanism for preventing rotation of said screw, and resilient means for yieldingly connecting said last named mechanism to said screw.

37. The combination with a supporting frame, of mining mechanism, extensible means comprising a non-rotatable screw for adjusting the elevation of said mining mechanism, extensible means for preventing rotation of said screw, and a spring for yieldingly holding the upper end portion of said screw connected to the upper end of said extensible rotation preventing means.

In testimony whereof I have hereunto set my hand.

NILS D. LEVIN.
